DESIGN FOR A BRACELET

Lena M. Smith, San Jose, Calif.

Application October 29, 1945, Serial No. 123,290

Term of patent 14 years

(Cl. D45—4)

To all whom it may concern:

Be it known that I, Lena M. Smith, a citizen of the United States, residing at San Jose, in the county of Santa Clara and State of California, have invented a new, original, and ornamental Design for a Bracelet, of which the following is a specification, reference being had to the accompanying drawing, forming part thereof.

I claim:

The ornamental design for a bracelet, as shown.

LENA M. SMITH.
